CLAIM

I claim the ornamental design for a copper roof vent cover, as shown.

DESCRIPTION

FIG. 1 is a perspective illustration of a copper roof vent cover according to a preferred form of the invention.

FIG. 2 is a front elevation view of the copper roof vent cover of FIG. 1.

FIG. 3 is a left side elevation view of the copper roof vent cover of FIG. 1.

FIG. 4 is a right side elevation view of the copper roof vent cover of FIG. 1.

FIG. 5 is a rear elevation view of the copper roof vent cover of FIG. 1.

FIG. 6 is a plan view of the copper roof vent cover of FIG. 1; and,

FIG. 7 is a bottom view of the copper roof vent cover of FIG. 1.
